[57]**CLAIM**

The ornamental design for a golf ball dispenser, as shown and described.

DESCRIPTION

FIG. 1 is a front perspective view of a golf ball dispenser showing my new design;

FIG. 2 is a front view thereof;

FIG. 3 is a rear view thereof;

FIG. 4 is a side view thereof with both sides being the same;

FIG. 5 is a top elevational view thereof; and,

FIG. 6 is a bottom elevational view of that which is shown in FIG. 5.

The broken lines in FIG. 2 are for illustrative purposes only and form no part of the claimed design.

FIG. 1

FIG. 2

FIG. 3

FIG. 4

FIG. 5

FIG. 6
